[57] CLAIM

The ornamental design for a paint scraper handle, as shown and described.

DESCRIPTION

FIG. 1 is a top plan view of a paint scraper handle showing my new design;

FIG. 2 is a side elevational view thereof, the opposite side being a mirror image thereof;

FIG. 3 is a bottom view thereof;

FIG. 4 is a front end elevational view thereof;

FIG. 5 is a rear end elevational view thereof;

FIG. 6 is a top plan view of another embodiment of my new design employing a handle of greater length, the surface texture being only partially shown but being substantially continuous over the surface thereof; and FIG. 7 is a side elevational view of the embodiment of FIG. 6.
